UNITED STATES PATENT OFFICE.

HARRY W. SELLE, OF CHICAGO, ILLINOIS.

EXCELSIOR-KNIFE.

1,033,202.

Specification of Letters Patent.

Patented July 23, 1912.

Application filed April 19, 1912. Serial No. 691,826.

To all whom it may concern:

Be it known that I, HARRY W. SELLE, a citizen of the United States, residing at Chicago, in the county of Cook and State of Illinois, have invented a certain new and useful Improvement in Excelsior-Knives, of which the following is a full, clear, concise, and exact description, reference being had to the accompanying drawings, forming a part of this specification.

My invention relates to an improved construction of excelsior knife, that is, a knife adapted to be mounted in a machine substantially constructed for the purpose, by which the knife may be moved relatively to a block of wood and longitudinally along its surface so as to repeatedly take from the block thin continuous shavings of small width. Machines for operating knives of this kind are well known in the art and form no part of the present invention, as a result of which they are not herein shown or described.

Among the objects of my invention are, to produce a knife of the character described in which the shavings or excelsior produced shall consist of narrow strips entirely divided from each other and which shall be so formed that the excelsior as a whole will not be matted into undesirable chunks; a further object of my invention consists of constructing a knife of the kind described so that it will avoid side thrusts upon the knife and machine and accomplish its work with a minimum amount of power since preferably the cutting edges of the knife are so conformed that each cutting edge shears the wood.

The several drawings illustrating my invention are as follows:

Figure 1 shows one construction of my improved knife in bottom perspective illustrating the conformation of the grooves cut in the knife and their relation to the top portion thereof. Fig. 2 is a top view of the knife shown in Fig. 1. Fig. 3 shows the knife illustrated in Figs. 1 and 2 in position upon a block of wood being cut thereby. Fig. 4 is a cross-sectional view of the knife shown in Figs. 1, 2 and 3. Fig. 5 shows in a view similar to Fig. 4 a modified construction of knife.

Similar numerals refer to similar parts throughout the several views.

As shown in Figs. 1, 2, 3 and 4, the knife 1 consists of a piece of steel of the general

conformation ordinarily employed in wood-working for removing shavings from blocks of wood, the end of the knife being beveled as shown at 2. The top face of the knife has milled therein a plurality of grooves so conformed and disposed as to leave a plurality of tongues 3 between which are disposed grooves 4, between which grooves and tongues are disposed upon either side thereof additional V shaped grooves 5 and 6 having opposite inclinations and so conformed that the wall of the grooves adjacent to one of the tongues 3 is at substantially right angles to the face of the knife while the other wall serves to join the bottom of the tongue with the outer edge of the adjacent wall of the next groove 4. It is essential that the side walls of the tongues 3 and the grooves 4 be substantially perpendicular to the face of the knife as this serves to effectively prevent the formation of "ribbon." It will be noticed that the V shaped grooves 5 and 6 form the side walls of the tongues 3.

As a result of the construction described, the shearing cuts come upon the cutting edges formed by the grooves 5 and 6 in opposite directions, thus producing no resultant side thrust upon the knife 1 or the block upon which it is operating. The cutting edges 5 and 6 of the knife serve to throw the shavings formed by them away from the grooves 4 and toward the shavings formed by the tongues 3, which operation results in making a fluffy, spongy mass of shavings which is the condition desired. Furthermore, each cutting surface, it will be observed, is separated from each adjacent cutting surface by a vertical wall which effectively separates the shavings into narrow strips and prevents the formation of strips having a width of more than one of the cutting edges 3, 4, 5 and 6, or, as is known in the art "ribbon." Were the grooves 4 omitted, in many cases "ribbon" would be formed extending between adjacent ones of the tongues 3 which would seriously interfere with the effectiveness of operation of the knife.

In Fig. 3, the knife is shown in operating position upon a block 7, the shavings turned up from the various cutting edges being indicated in this view. It will be observed that the shavings 3^a and 4^a formed by the cutting edges 3 and 4 respectively, curl up in line with the motion of the knife somewhat in advance of the cutting edges while

the shavings 5^a and 6^a are turned away from the shavings 4^a and toward each other, as a result of which the shavings cannot wind up together to produce a solid mass. In the 5 modified construction of knife shown in Fig. 5, the grooves 15 and 16 are similar to the grooves 5 and 6 in the construction of knife shown in Figs. 1, 2, 3 and 4. The modified construction differs from the construction 10 above described in that the tongues 13 are provided with inclined cutting edges which are oppositely inclined so that the shearing action resulting from these cutting edges is balanced, producing no resultant side thrust 15 upon the machine; also the cutting edges of the grooves 14 are inclined in opposite directions so that shearing cuts are the result which balance each other, thus producing no resultant side thrust upon the knife and 20 machine. The inclination of the cutting edges 13 and 14 in the modification shown in Fig. 5 is about one-half that of the cutting edges 15 and 16, as a result of which all of the advantages incident to the 25 construction of knife shown in Figs. 1 to 4 inclusive, are retained with the additional advantage that all of the cuts are shearing cuts. Complete separation is effected between the different shavings formed by 30 using grooves 14 between the tongues 13 and having oppositely inclined shearing edges 15 and 16 between the tongues and the grooves.

From the above it will appear that my invention consists in arranging shearing surfaces in such a manner that alternate tongues and grooves are formed in the cutting blade which are joined by oppositely disposed inclined cutting surfaces. The 40 alternation of the tongues and grooves positively separates the shavings to prevent the formation of "ribbon," and the arrangement of shearing surfaces, whether upon all of the cutting edges or only upon the 45 cutting edges of the V shaped grooves, materially reduces the amount of power required to drive the machine, and also prevents side thrust upon the moving parts.

What I claim is:

50 1. An excelsior knife having a beveled cutting edge extending across one end and

a plurality of alternating tongues and grooves having side walls substantially perpendicular to the face of the knife formed longitudinally in its face extending from the 55 cutting edge, there being V shaped grooves of opposite inclination between each of the first named grooves and the adjacent tongues, said V shaped grooves being bounded in part by the said walls of the 60 tongues, the outer surface of the tongues and the bottom surface of the grooves being oblique relatively to the side walls of the grooves and of alternating inclination to produce separate shearing cuts. 65

2. An excelsior knife having a beveled cutting edge extending across one end and a plurality of alternating tongues and grooves having side walls substantially perpendicular to the face of the knife formed 70 longitudinally in its face extending from the cutting edge, there being V shaped grooves of opposite inclination between each of the first named grooves and the adjacent tongues, said V shaped grooves being bounded in part by the said walls of the tongues. 75

3. An excelsior knife having a beveled cutting edge extending across one end and a plurality of alternating tongues and grooves having side walls substantially perpendicular to the face of the knife formed longitudinally in its face extending from the cutting edge, there being V shaped grooves of opposite inclination between each of the first named grooves and the adjacent 80 tongues, said V shaped grooves being bounded in part by the said walls of the tongues. 85

In witness whereof, I hereunto subscribe my name this 8th day of April, A. D. 1912. 95

HARRY W. SELLE.
